METHOD AND MACHINE FOR TEXTILE PRINTING

Benjamin Champlin Moffatt, Rock Hill, S. C., assignor to Rock Hill Printing and Finishing Company, Rock Hill, S. C.

Application January 19, 1934, Serial No. 707,413

9 Claims. (Cl. 101—178)

This invention relates to new and useful improvements in the art of fabric printing, and more particularly to a method and machine whereby a conventional printing machine may be utilized for printing two strands of cloth or fabric simultaneously.

Another important object of the present invention is to provide improvements in a conventional fabric printing machine for printing two strands of fabric simultaneously with the least possible number of modifications of the conventional machine.

These and various other important objects and advantages of the invention will become apparent to the reader of the following specification.

In the drawings:—

Figure 1 represents a diagrammatic view disclosing the travel of the two cloth strands and their corresponding gray cloth over the various tension bars, rollers and drying elements.

Figure 2 represents a fragmentary side elevational view of the apparatus, showing the printing machine in the act of printing two strands simultaneously.

Figure 3 represents a vertical sectional view fragmentarily showing the drying cans for the rear strand gray cloth and the pit through which this cloth and also its corresponding printed strand travels.

Figure 4 represents a sectional view taken substantially on line 4—4 of Figure 3.

Figure 5 represents diagrammatic views showing the line of travel for each of the printed strands over the drying cans.

Referring to the drawings wherein like numerals designate like parts, it can be seen in Figure 1 that numeral 5 generally refers to the conventional printing machine which includes the drum 6 and the forward printing rollers 7, as well as the rearward printing rollers 8. Numeral 9 represents the usual endless rubber blanket which surrounds the drum 6 and which is trained over suitable rollers 10 and 11, all in a conventional manner well known in the art.

Numeral 12 represents the usual roll for the strand stock A, while numeral 13 represents the usual roll from which the gray cloth A', complementary to the strand A, is fed.

In carrying out the present invention, an additional strand roll 14 is provided for the supple-

mental strand B, while a roll 15 is provided adjacent the roll 14 for the gray cloth B' which is complementary to the strand B.

At the rear of the machine is the usual roll 16 on which the gray cloth B' is wound after the same passes over the vertical arrangement of gray cloth drying cans 17.

At the front of the machine is the supplemental vertical arrangement of cans 18 over which the gray cloth A' is trained and dried, after which it passes to the winding roll 19.

Above the printing machine 5, and perhaps on the floor above the printing room, is located the usual drying cans C', C², and C³, as well as the drying cans D', D², and D³.

In connection with the conventional machine, all six of these cans are utilized for the single strand being printed, but in connection with the present invention, these cans are divided so that the top row takes the printed strand A, while the lower row takes the other strand B.

In order to obtain the maximum drying surface of the drying cans or cylinders last mentioned, the strand A passes over the first can C' and over and almost entirely around the second can C², where it is trained over and backwardly by way of the small rollers 20 to engage against the first can C'. A substantial surface of the can C' is engaged and the strand moves rearwardly by being trained over the small roller 21. The strand then passes under all of the cans, as shown in Figure 1. This last mentioned flight of the strand A is trained backwardly over the small roller 22 and then passes backwardly over the last can C³ and from there to the usual folding machine (not shown).

The strand B passes upwardly over the can D' and under the smaller can D² from where it passes upwardly over the can D² and then forwardly to the small roller 23 from where it extends rearwardly to the small roller 24. From the small roller 24, it extends forwardly and over and almost entirely around the can D³ where it is directed upwardly by the small roller 25 and after passing over the small roller 26 adjacent the strand A, it moves toward the folding machine (not shown).

Thus it can be seen that as much of the heating surfaces of the drums or cans is utilized in drying the strands A—B as is possible. In other

words, because of the arrangement of the strands over the cans, the conventional number of six can still be utilized to accommodate two independent strands.

5 Reverting to the machine generally referred to by numeral 5, it can be seen that the strand B passes from the roll 14 and with its gray cloth B' goes between the gray cloth A' and the drum 6 of the machine 5, with both the forward and 10 rearward groups of printing rollers 7 and 8 bearing against the same, but with only the forward printing roller 7 acting against the same, as the strand A passes between the rear printing rollers 8 and the aforementioned strand B and takes 15 printing from only the rear rollers 8 and passes out of the machine at the bottom thereof between the forward and rearward groups of printing rollers. From there, the strand A and its gray cloth A' pass into a floor pit 28 and are directed horizontally by the rollers 29-30, respectively. A suitable flooring or platform 30 is disposed over this pit and serves to protect the webs travelling thereunder and through the pit so that the attendant's location will be available as well as supporting area for the cans 18.

20 Adjacent the cans 18 which are supported upon brackets 31 carried by posts 32, the gray cloth A' goes upwardly through an opening 33 in the platform 30 to engage with the uppermost can 18 and 25 zig-zagging back and forth over these cans, the same departs at the lowermost can to pass under the small roller 34 and wind on the roll 19, the latter being supported by a bracket 35 carried by the post 36.

25 The strand A continues forwardly beyond the outlet of the gray cloth A' and leaves through an opening 37 in the forwardmost end of the platform 30, and extends upwardly over the small roller 38 in its travel to the first drying can C'. 30 Thus it can be seen that the apparatus in front of the printing machine will not interfere with the attendant and as a matter of fact, the attendant in front of the machine may be available for care of the cans 18 and the winding roll 19.

35 Figure 2 shows more clearly how the strand A is paid from the roll 12 and as is clearly shown in Figure 2, this strand A, as well as its gray cloth A', is trained over tension bars 39 and 40, respectively, and over small rollers 41 in their travel 40 toward the machine 5. These tension bars 39-40 are supported by suitable uprights 42 and suitable double brackets 43 on these uprights 42 support the rolls 12 and 13 and in a like manner the additional rolls 14 and 15 are supported.

45 It will thus be seen that with my improvements a separate gray cloth is provided for each of the two webs to be printed so that the usual endless blanket, such as indicated by the numeral 9, in Fig. 1, is protected since the two gray cloths A' and B', take up the surplus color impression passing through the webs A and B, as they are being printed upon and thus afford protection for the said endless blanket, which is an item of considerable importance. The arrangement and location of the flooring or platform 30, over the pit 28, which latter provides the path of travel of the web A, and its associated gray cloth, also serves to protect the travelling webs that are first deflected from the printing machine and at the same time enables the operator to take his usual position at the front of the machine where he can maintain a close inspection over the work of the machine and replenish the color troughs with 50 color, which latter is required quite frequently.

5 It can be seen that the conventional machine has been improved to the extent that the cans 18 have been added to accommodate the extra strand and that the usual number of six or more cans for drying a single strand have been divided 5 to accommodate two strands.

10 While the foregoing specification sets forth the invention in specific terms, it is to be understood that numerous changes in the shape, size and materials may be resorted to without departing 10 from the spirit and scope of the invention as claimed hereinafter.

15 Having described the invention, what is claimed as new is:—

1. A structure for use in conjunction with multiple web textile printing machinery comprising in combination, a floor pit, a web protecting platform disposed over the said pit, said platform having a slot therein at one end thereof for receiving a printed strand and a gray back, a series 20 of gray back drying cans and a winding gray back roll therefor mounted over the opposite end portion of the platform, said platform being provided with a printed strand outlet slot at the last mentioned end of the platform, and said platform at 25 its intermediate portion being provided with an outlet slot through which the gray back can be trained to the cans and winding roll.

2. Multiple web printing apparatus comprising an impression cylinder and separate sets of printing rolls cooperating with opposite portions of the periphery thereof, supporting racks located at substantially floor level for removably and rotatively supporting two sets of rolls, each set consisting of a rolled web to be printed upon and a 30 roll of gray cloth, separate guiding means located above the racks for training the said webs to be printed and their associated gray cloths, all in spaced relation to a common point adjacent the impression cylinder and for assembling the same 35 in superposed relation and directing them between the surface of the impression cylinder and the first set of printing rolls, with the outermost web in impression receiving relation with said last named rolls, means for downwardly deflecting the said printed web and its associated gray cloth immediately they have passed the said printing rolls, means for causing the other web and its associated gray cloth to continue its travel with the cylinder past and into contact with the 40 succeeding set of printing rolls, a protective floor for the web at substantially floor level in front of the machine, means for guiding the deflected web and its associated gray cloth beneath the said floor, two sets of drying cans located above 45 the printing apparatus, and means for leading each printed web upward thereto and for training one web partially about the peripheries of one set of said cans and the other web partially about the peripheries of the other set of cans.

3. Multiple web printing apparatus for simultaneously printing upon a plurality of fabric webs, comprising a printing machine including an impression cylinder and separate sets of printing rolls grouped about the surface thereof, racks for 50 removably and rotatably supporting a plurality of sets of rolls, each set consisting of a roll of fabric to be printed and an associated roll of so-called gray cloth, said racks being arranged to support the rolls adjacent the floor level and at 55 the rear of the printing machine, means for training the webs from the several sets of rolls in separate pairs upwardly and then forwardly toward the impression cylinder, means for assembling and superimposing all the webs of the sets 60

at a point adjacent the surface of the impression cylinder and the first set of printing rolls, means for causing the superposed webs to travel with the cylinder, means for downwardly deflecting the outermost printed web and its associated gray cloth after they have passed the first set of printing rolls and for causing the other web and its associated gray cloth to travel with the cylinder past the second set of printing rolls, a web 10 protecting flooring in front of the printing machine also providing an operator's station, means for training the deflected web and its associated gray cloth beneath the flooring and then upward at the end thereof, a receiving roll for the gray 15 cloth at the outer end of the flooring, separate sets of drying cylinders located above the printing machine, and means for training each of the printed webs upwardly to the said drying cylinders, one partially around one set and the other partially around the other set, the said deflected web being trained to travel over the said flooring to the upper set of drying cylinders.

4. Multiple web printing apparatus for simultaneously printing upon a plurality of fabric webs, comprising a printing machine including an impression cylinder and separate groups of printing rolls associated with the periphery thereof, separate racks for removably and rotatably supporting a plurality of sets of rolls, each 30 set consisting of a rolled web of fabric to be printed and an associated rolled web of gray cloth, said racks being arranged to removably support the rolls adjacent the floor level of and at the rear of the printing machine, means for 35 training the separate sets of webs from their rolls upward and then forward toward the impression cylinder of the printing machine and for maintaining them in spaced relation while being so trained, means for superimposing all the webs and for causing them to pass between the cylinder and the first group of printing rolls to print upon one of the webs, means for separating and 40 downwardly deflecting the printed web and its associated gray cloth, a web protecting flooring at the front of the printing machine providing a workman's station, means for training the printed web and its gray cloth longitudinally beneath the platform and then upwardly and forwardly in a travel path above the said flooring, means 45 for training the other printed web and its associated gray cloth upward from the printing machine, and means for separating the gray cloth from the printed web and for training it rearwardly to a take-up roll.

5. Multiple strand printing apparatus for simultaneously printing upon a plurality of fabric webs, comprising a printing machine including a drum and associated forward and rearward groups of printing rollers, pairs of racks adjacent the floor level of the machine for removably and rotatably supporting a pair of fabric roll strands and a pair of complementary gray cloth rolls, means for directing the said fabric strands and gray cloth strands in alternate pairs upwardly from their roll racks and forwardly into and through the printing machine so that one group of printing rollers will print upon one strand and the other group will print upon the other strand, a web protecting platform at the front of the machine, means for directing the first printed strand and its associated gray cloth from the printing drum to and beneath the flooring, a gray cloth winding roll adjacent the end of the flooring upon which one of the gray cloths 70 may be wound, means for training its associated

printed strand upwardly from and then forwardly above the flooring, means for training the other printed strand upwardly, two separate superposed sets of drying cans located above the printing machine, means for training one printed strand around the periphery of and longitudinally across one set of said cans and for training the other printed strand around the periphery of and longitudinally across the other set of cans and for delivering the strands separately from the dry- 10 ing cans.

6. The construction and arrangement of elements specified in claim 5, and including a vertical series of drying cans located adjacent the end of the flooring and about which one of the gray 15 cloths is trained and dried before it is wound about its winding roll.

7. Multiple web printing apparatus comprising an impression cylinder and separate sets of printing rolls cooperating with opposite peripheral portions thereof, separate pairs of supporting racks located at substantially floor level in rear of the impression cylinder for removably supporting two sets of rolls, each set consisting of a rolled web to be printed upon and a roll of gray 25 cloth, separate guiding rollers located above each rack for training the said webs to be printed upon and their associated gray cloths in spaced relation to a common point adjacent the impression cylinder and for there assembling and directing 30 them in superposed relation between the surface of the impression cylinder and the first encountered set of printing rolls with the outermost web in impression receiving relation with said last-named rolls, means for downwardly deflecting 35 the said printed web and its associated gray cloth from said rolls to a point at substantially the floor level of the machine and for guiding them forward, means for causing the other web and its associated gray cloth to travel with the impression 40 cylinder and in cooperative printing relation with the succeeding set of printing rolls, two separate superposed sets of drying cans located above the impression cylinder, and means for directing each printed web upward thereto and for training 45 the web first printed partially about the peripheries of the upper set of drying cans and for training the other printed web partially about the peripheries of the lower set of drying cans.

8. The construction and arrangement of elements specified in claim 7, and including a take-up roll mounting for each gray cloth, one located in front of and spaced from the printing machine, and the other located at the rear of the machine beyond the brackets for the web and 55 gray-cloth supporting rolls.

9. Multiple web printing apparatus comprising a printing machine including an impression cylinder and separate sets of printing rolls cooperating with opposite peripheral portions thereof, two 60 separate pairs of roll-supporting racks located at substantially floor level in rear of the machine for removably supporting two separate sets of rolls, each set consisting of a rolled web to be printed upon and a roll of gray cloth, means for guiding and training the two sets of webs upwardly from their respective roll racks and then forwardly and assembling them in superposed relation between the surface of the impression cylinder and one set of printing rolls, means for 65 downwardly deflecting the said printed web and its associated gray cloth out of the machine and for training them forwardly at substantially floor level, means for causing the other web and its associated gray cloth to continue their travel with 70 75

the cylinder in cooperative printing relation with the succeeding set of printing rolls, a separate re-winding roll rack for each gray-cloth roll one located in front and the other in the rear of the printing machine, the construction and arrangement of parts being such that each web to be

printed will be backed by a separate and renewable gray-cloth during the travel of the two sets of webs through the printing machine, and a protective flooring overlying the said forwardly trained web first printed upon.

BENJAMIN CHAMPLIN MOFFATT.
